J. R. WADE

AUTOMATICALLY OPERATING FABRIC CLAMPING AND GRIPPING BUCKLE

Filed Oct. 2, 1922

UNITED STATES PATENT OFFICE.

JEM R. WADE, OF DENVER, COLORADO, ASSIGNOR OF ONE-HALF TO THE NEW ENGLAND ELECTRIC COMPANY, OF DENVER, COLORADO, A CORPORATION OF COLORADO.

AUTOMATICALLY-OPERATING FABRIC CLAMPING AND GRIPPING BUCKLE.

Application filed October 2, 1922. Serial No. 591,994.

To all whom it may concern:

Be it known that I, JEM R. WADE, a citizen of the United States of America, residing at the city and county of Denver and 5 State of Colorado, have invented new and useful Automatically-Operating Fabric Clamping and Gripping Buckles, of which the following is a specification.

My invention relates to a new type of an 10 automatically operating fabric clamping and gripping buckle for gripping the ends of sanitary napkins, stockings, and other fabric articles.

And the objects of my invention are:

15 First: To provide an automatically operating fabric gripping buckle that can be easily and quickly attached to the ends of sanitary napkins, and that will firmly clamp them against accidental movement or displacement at any part of their end portions, and that is free from fabric penetrating members, and that can be quickly released from the said end portions.

Second: To provide an automatically operating fabric gripping buckle that is adapted to be clamped to the upper ends of stockings or other articles, and that is arranged and adapted to be quickly attached to them to hold and support them in unwrinkled positions, and that is provided with such smooth surfaces that it does not engage the wearer with frictional pressure, and that can be instantly released from the article.

Third: To provide an automatically operating fabric gripping buckle that will clampingly grip the free ends of fabrics with an increasingly tightened hold as the fabrics are tightened, and without in any way puncturing or fraying or tearing the fabric, and 40 that is made preferably of wire and is very light of weight, and can be easily and cheaply made.

I attain these objects by the mechanism illustrated in the accompanying drawings, 45 in which:

Figure 1 is a perspective view of my automatically operating fabric clamping gripping, but quickly releasable buckle secured to the pendant portions of a waist belt.

50 Fig. 2 is a front view—full size—of the improved fabric gripping buckle.

Fig. 3 is a vertical, sectional view through the same, showing the manner in which the

end of a fabric article is clamped between the two parts of the buckle. 55

Fig. 4 is a view showing its adaptation as a stocking supporter. And

Fig. 5 is a front view showing the device arranged for use in connection with towels and like articles. 60

Similar letters of reference refer to similar parts throughout the several views.

Referring to the drawings:

The numerals 1 and 2 represent the opposite portions of a piece of suitable wire 65 that is bent into several shapes to form the main or base portion of the improved buckle, and the several shapes of the wire and the base of the buckle is formed in the following manner: The parts 1 and 2 of the 70 wire are bent to form horizontal portions which are united by a sleeve 3 that is tightly forced over them to form a bar, and the opposite portions of the wire beyond the sleeve are bent upon themselves into small loops 4 75 to form reverse or inwardly extending horizontal portions 5 of the loop, which may be made as long as desired, but preferably about an inch to two inches long as desired, for sanitary napkins and for stockings. 80

The loops 4 are made large enough to form a space between the outside sleeve 3 and the inside horizontal portions 5, to allow the sleeve to receive the lower end of a piece of fabric or ribbon that forms the 85 pendant 6 on the waist belt 7, and the end of the pendant is sewed or otherwise secured around the sleeve 3 to the pendant.

The short horizontal portions 5 extend inward toward each other and then terminate in short semi-circular bends 8, which are separated from each other by a suitable space, and from the terminal ends 8 the wire is bent to form a depending triangular or heart-shaped frame A, the contracted 95 end 9 of which points downward. The heart-shaped frame A, with its horizontal bar 3, forms the main or base member of the improved buckle or clamping device, and to this main frame A is hinged a clamping 100 member B, in the following manner:

The clamping member comprises an incomplete heart-shaped frame, the free ends of which are formed into eyes 10, which encircle the horizontal members 5 of the main 105 frame close to the semicircular terminals 8.

and thus form a hinge connection with the said horizontal members 5.

The clamping member B does not coincide throughout with the outline of the main frame A, but its upper end portions 11 adjoining the eyes 10 are bent on a curve of a greater radius than the corresponding portions of the main frame 10, so that the clamping frame at these points, instead of coinciding with the corresponding curved corners of the main frame, extends across and slightly inside these corners and rests upon the sides and top portions of the main frame, and not upon its curved upper corners. This arrangement gives the clamping frame a firm bearing on the main frame and prevents either side member of the clamping frame from slipping over the adjacent corner of the main frame when the buckle 20 is in use, as will be understood by reference to Figure 2. Also, the lower end of the clamping frame terminates slightly above the corresponding end of the main frame, which effects a better clamping action than 25 would obtain if both frames were of the same length.

In Figure 1 of the drawings, the improved clamping buckle is shown in connection with supporting means for women's sanitary napkins, and in this adaptation, one of the buckles is secured to each of two opposite depending straps 6, which are secured to a waist band or belt 7. In securing the napkin, each end is passed through both 30 frames of the buckle so as to rest in the contracted lower ends of the same; the free end of the napkin is then passed around and under the end of the clamping frame and back through the main frame, beneath the body portion of the napkin, as shown in Figure 3, a short length of the said end portion depending below the buckle. The pull exerted upon the ends of the napkin acts to 35 draw the clamping members of the buckle towards the main frames of the same, thereby clamping the ends of the napkin firmly between the two members of the buckle, and as the ends of the napkin are held in the contracted ends of the buckle frames, the 40 fabric is thereby crowded into a continuously narrowing space, under the pull exerted upon the napkin, by which the clamping action upon the ends of the napkin is augmented. As there is always more or less 45 pull on the napkin, there is no danger of the ends of the napkin becoming disconnected from the clamps.

In Figure 4 of the drawings I have illustrated the improved buckle in connection 50 with a stocking supporter. In this arrangement, the buckle is secured to a strap 12 which depends from a triangular ring 13, to which is secured the ends of the usual strap 14, which is passed around the leg 55 of the wearer below the knee. As a stocking

supporter, the buckle is preferably made of smaller size than when used for other purposes, but in other respects it is the same character of buckle as that shown in Figures 1 and 2.

In Figure 5 of the drawings is shown a front view of the improved buckle, as adapted for use in connection with towels and like articles. In this arrangement, the sleeve 3 is omitted, and the horizontal terminal end portions of the main frame of the buckle are confined in the folded portion 15 of a metal plate 16, which is bent upon itself midway of its length. The fold 15 tightly surrounds the end portions of the buckle, and the flat 75 portions of the plate are pressed into engagement with each other, and are provided with nail or screw holes 17, by which the plate may be secured to a fixed object, thus 80 securely supporting the buckle.

The improved buckle presents many advantages over buckles in general use, chief among which are the quick and easy manner of securing the same upon an article, and absence of parts that would tear garments, or 85 injure the wearer.

Having described my invention, what I claim as new and desire to secure by Letters Patent, is:

1. A fabric clamping device of the character described, consisting of a wire frame-like member comprising a horizontal bar portion of suitable length, which is bent at points defining the length of the bar, to form inwardly extending members which lie beneath and are parallel with the bar, said members being bent in reverse directions, and then around to form an incomplete ring-like member, and a second incomplete ring-like member, of substantially the same size 100 and shape as the first ring-like member, the free ends of which are bent around the said inwardly extending members to form a hinge connection therewith.

2. In a fabric clamping device of the character described, a wire which is bent centrally of its length to form an incomplete ring-like member, the opposite lengths being then bent outward in opposite directions to form short horizontal portions which terminate in reverse bends to form a divided horizontal bar, a sleeve tightly surrounding said divided horizontal bar, and an incomplete ring-like member of substantially the same size and shape as the first ring-like 105 member, the free ends of which are bent around the said short horizontal portions, to form a hinge connection therewith.

3. In a fabric clamping device of the character described, a wire which is bent centrally of its length to form an incomplete heart-shaped frame, the opposite length of wire being then bent outward in opposite directions to form short horizontal members which terminate in reverse bends to form a 110

divided horizontal bar, a retaining sleeve rigidly secured upon the said divided horizontal bar, and an incomplete heart-shaped frame of the same size as the first frame, 5 the free ends of which are bent around the said short horizontal members to form a hinge connection therewith.

4. In a fabric clamping device of the character described, an incomplete heart-shaped main frame, the opposite members of which 10 are bent outwardly in opposite directions to form short horizontal members, and then inwardly to form a divided horizontal bar, a retaining sleeve secured around said horizontal bar, said bar providing for attachment 15 thereof of a depending support, an incomplete heart-shaped clamping frame of

substantially the same size as the main frame, the free ends of which are bent around the said short horizontal members to 20 form a hinge connection therewith, said clamping frame being adapted to hold the end of a fabric article between itself and the main frame when said end is passed through both frames, and around the contracted portion 25 of the clamping frame, and back through the main frame.

In testimony whereof I affix my signature in presence of two witnesses.

JEM R. WADE.
